In Switzerland November 30, 1937

10 Claims. (Cl. 102—30)

Since armies have been motorized and the enormous extension of military aviation, researches for a small bore projectile have been made such projectile fired into tanks or fuel lines or pipes of motor vehicles or into airplane wings would put these vehicles out of action either by fire or by large perforations.

While such results are now practically attained by special medium bore projectiles of 20 mm. or more, they have not yet been attained by small bore projectiles used for military rifles or quick firing guns of 6 to 15 mm. bore.

Numerous attempts have been made in that direction without appreciable results. As incendiary projectiles it will be sufficient to remember the phosphorous ones and the trading bullets which, from specialists' unanimous opinions, give only precarious or irregular results.

The present invention refers to a small size projectile having incendiary or explosive properties for use with current military rifles or quick firing guns.

Outwardly this projectile cannot be distinguished, in any way, from an ordinary bullet for a military rifle.

However, instead of being a solid metal bullet, or a metal core covered with a hard metal shirt, it is hollowed throughout its length. The hollow part contains first a fulminant charge or load in which is placed a hard body, intended to cause the inflammation of the charge, when impact occurs, and next a charge of pyrotechnical or explosive composition. The projectile is sealed by a plug which for an incendiary projectile is expelled by the internal pressure caused by the deflagration of the charges, thus letting out of the projectile a sufficient quantity of incandescent matter capable of setting fire to any combustible material surrounding the impact point.

In case of an explosive projectile, all of the metallic shell is torn, even pulverized by the blowing up of the internal explosive charge.

The only figure of the annexed drawing shows as an example a longitudinal sectional view of a projectile according to the present invention.

This projectile is hollowed throughout its length. This hollowed out portion may be a bore of equal diameter or of different diameters according to any desired design. In the drawing the forward nose portion is shown to have a smaller diameter than the rear portion. In the hollow pointed arch or ogive, is lodged a relatively heavily compressed fulminant priming charge *a*.

Right in the centre of the fulminant priming

charge is placed a hard body *b*, for instance made of metal, and which is free from the inside walls of the bullet, and having no contact whatever with said walls.

Following the priming fulminant charge is a composition *c* compressed into the hollow shell of the bullet, which for an incendiary projectile could be of pyrotechnical composition, such as metallic powders or other similar material, but giving a tremendous ignitive heat, or for an explosive projectile, this composition *c* could be explosive, for instance tetraniro-pentaerythrite could be used, which means very high bursting powder results. If desired both incendiary and explosive charges, suitably arranged, may be provided.

Finally behind the composition *c* comes a plug of metal or other suitable material sealing the shell of the bullet, which can be set or forced into the bevel of the shell of the projectile. In case of an incendiary bullet, the plug *d* is fixed to the shell of the bullet in such a way that it can be expelled far away by the suddenly growing internal pressure happening within the body of the bullet.

The working of the thus described projectile is as follows:

When it is fired, it comes out of the barrel of the small bore arm as an ordinary solid bullet. The composition *c* cannot be ignited or exploded when the shot is fired, because experiences have proved that first the propulsion action of the gases of the cartridge powder is progressive and does not give a sufficient impact to bring the fulminant charge *a* to detonation. The sensitivity of the fulminate powder is controlled by the hardness of pack (pressure in loading) and it is very easily packed so that it will not explode at set back while the sensitivity is readily, easily and accurately controlled by regulating the packing pressure. Also there is no heat caused by friction between pointed arch of the shell of the bullet and inside of the arm barrel, since there is no contact of these parts.

When, on its trajectory, the projectile hits an obstacle offering resistance to its progress, as for instance the metal sides of a tank, an airplane wing, an armored plate, etc. the percussion due to the inertia of the hard body lodged in the priming charge, or to the impact, taking place between the walls of the projectile and the hard body, instantly fires the fulminant charge *a*.

The latter in turn fires the composition *c*.

Should this last composition possess pyrotechnical qualities, meaning that the projectile is in-

cendiary, the instantaneous internal pressure generated from gases within the bullet expels the plug *d* backward, thus opening the base of the bullet through which incandescent metallic particles or other incendiary material can be forcibly expelled.

However account must be taken that during the very short duration of the phenomenon, all the mass of the bullet itself and its content, ignited matter, etc., owing to acquired velocity of projectile and inertia, keeps on moving from rear to front of projectile and at same velocity that projectile itself which is, as well known, of hundreds of feet per second.

15 The two motions, be it the forward one, proper to the projectile or the backward one, proper to the gases and incandescent particles emitted from the bullet after percussion, have a tendency to neutralize, since they are contrary.

20 Provided a sufficient rapidity of the deflagration of pyrotechnical matter contained in the bullet occurs, the result of the two motions is an emission, at the bullet percussion point or immediately surrounding it, of gases and incandescent metallic particles, which in turn regularly ignite the surrounding mixture of air and fuel escaping from tanks or pipes stricken by the projectile.

If the composition *c* is an explosive one, the projectile bursting occurs in a very small fraction 30 of a second, after the impact of the projectile against an obstacle, an airplane wing for instance.

The different shattered parts of the projectile, keeping their component motion, in the same direction as the projectile trajectory, nearly all 35 receive at the explosion time a compounded motion perpendicular to the projectile trajectory. These two components add their effects, with the results that the projectile parts are showered at the stricken obstacle, in a slanting way from the 40 original trajectory, and owing to this fact astonishing destructive effects are obtained.

Owing to the ratio between the mechanical resistance of the projectile shell and the potential of the explosive composition, the results obtained 45 with this projectile can be quite different; it can be designed or manufactured to cover special definite aims.

The thickness of the walls, the profile of the nose portion or "ogive" of the ball, the diameter 50 of the solid metal body located within the nose portion, and the more or less important compression of the fulminant charge regulate the sensitivity of the ball in a perfect manner. Due to these arrangements a very high degree of security may 55 be attained by use of the ball according to the invention, premature explosion on firing will be precluded while regular and precise actuation upon an obstacle offering a certain resistance will be insured.

60 What we claim is:

1. A projectile comprising a shell having a longitudinally disposed bore, detonating material in the forward end of said bore, an explosive charge adjacent said detonating material in the 65 rear portion of said bore and a substantially spherical metal body embedded in said detonating material and completely surrounded therewith, whereby when said projectile strikes an object the substantially spherical metal body will ignite the said fulminate and explosive charges.

2. A projectile comprising a shell having a longitudinally disposed bore, detonating material in the forward end of said bore, an incendiary charge adjacent said detonating material in the 70 rear portion of said bore and a substantially

spherical metal body embedded in said detonating material and completely surrounded therewith, whereby when said projectile strikes an object the substantially spherical metal body will ignite the said fulminate and incendiary charges. 5

3. A projectile comprising a shell having a longitudinally disposed bore, detonating material in the forward end of said bore, an explosive charge adjacent said detonating material, an incendiary charge adjacent said explosive charge 10 and a substantially spherical metal body embedded in said detonating material and completely surrounded therewith, whereby when said projectile strikes an object the substantially spherical body will ignite the said charges. 15

4. A projectile comprising a shell having a longitudinally disposed bore, detonating material in the forward end of said bore, an explosive charge adjacent said detonating material, an incendiary charge adjacent said explosive charge, 20 an explosive charge adjacent said incendiary charge, and a substantially spherical metal body embedded in said detonating material and completely surrounded therewith, whereby when said projectile strikes an object the substantially 25 spherical metal body will ignite the said charges.

5. A projectile as claimed in claim 1, where said substantially spherical metal body is a steel ball.

6. A projectile as claimed in claim 2, wherein 30 said substantially spherical metal body is a steel ball.

7. A projectile as claimed in claim 3, wherein 35 said substantially spherical metal body is a steel ball. 35

8. A projectile comprising a shell having a pointed nose portion and a blunt end portion, a bore longitudinally disposed in said shell, the forward end portion of said bore in the nose portion of said shell having a smaller diameter than the major rear portion of said bore, detonating material packed within said small diameter of said bore, an explosive charge packed within the rear portion of said bore, a solid substantially spherical steel ball embedded in and entirely surrounded by 45 said detonating material.

9. A projectile comprising a shell having a pointed nose portion and a blunt end portion, a bore longitudinally disposed in said shell, the forward end portion of said bore in the nose portion of said shell having a smaller diameter than the major rear portion of said bore, detonating material packed within said smaller diameter of said bore, an explosive charge packed adjacent said detonating material, an incendiary charge packed within the rear portion of said bore and a solid substantially spherical steel ball embedded in and entirely surrounded by 55 said detonating material.

10. A projectile comprising a shell having a 60 pointed nose portion and a blunt end portion, a bore longitudinally disposed in said shell, the forward end portion of said bore in the nose portion of said shell having a smaller diameter than the major rear portion of said bore, detonating material packed within said smaller diameter of said bore, an explosive charge packed adjacent said detonating material, an incendiary charge packed adjacent said explosive charge, an explosive charge packed within the rear portion of said 65 bore and a solid substantially spherical steel ball embedded in and entirely surrounded by said detonating material.
